Application July 8, 1938, Serial No. 218,233

18 Claims. (Cl. 46—207)

This invention relates to energy storage mechanisms, and in particular to such mechanisms applied to automotive toys.

It is an object of this invention to provide an automotive toy having a body providing a complete enclosure for the means for imparting motion to the body.

It is a further object of this invention to provide a toy including energy storage means for storing energy in the motion imparting means both of which means are disposed wholly within the body.

It is a further object of this invention to provide a toy having a flexible, resilient, or deformable body cooperating with the energy storage means in such manner that the energy storage means may be operated by distorting, flexing or compressing the body.

It is a further object of this invention to provide a toy wherein the body provides for complete enclosure and protection of the motion imparting means and other mechanisms, to present only smooth, resilient and flexible exterior surfaces to prevent damage to a user, and in particular to infant users.

It is a further object of this invention to provide an automotive toy which is flexible or yieldable, and which is gasproof and water-proof.

It is a further object of this invention to provide a toy in the nature of a ball having a flexible, resilient, body of rubber or the like with means enclosed in the body for imparting motion to the ball.

It is a further object of this invention to provide a toy including a deformable body providing full enclosure for motion imparting means therefor, and deformable frame means supporting the motion imparting means, secured to or closely associated with the deformable body, and deformable therewith.

It is a further object of this invention to create a movable object having an operating mechanism therein, which mechanism is wound, or otherwise set in operation by a compression, or a series of compressions upon the body of the object.

A still further object of the invention is to make a self moving device in which the operating mechanism therein is supported by a resilient frame and in which energy is given to said mechanism through the exertion of pressure upon said frame and/or the body of said device.

These and other objects and advantages will appear from the following description taken with the drawing.

Toys of ball form with motion imparting means therein are well known; however, due to the necessity for winding, or otherwise storing energy in, the motion imparting means in said 5 toys by the use of strings, keys or toothed rods, or racks, the enclosure of the motion imparting means has always been rigid and partial rather than complete. The ball body was, therefore, necessarily provided with apertures for the insertion of energy storing instrumentalities or for the extension of permanent means, such as winding keys, from the interior to the exterior of the body.

The exposed metallic parts of the motion imparting means were therefore exposed to the atmosphere and subjected to destruction and loss.

In addition the necessity for using easily lost or misplaced insertable or attachable instrumentalities such as keys, winding strings and the like, was a distinct disadvantage. Where such winding instrumentalities were permanently attached to the toy they extended beyond the body and constituted potentially dangerous, unsightly, and awkward projections. The projections rendered the toys dangerous and in some cases, prevented the use of the toy by infants of early age.

Furthermore, the operations of winding by keys or insertable racks and strings were operations incapable of being performed with ease, or by infants of early age.

By utilizing the principles of this invention all of the above enumerated disadvantages are obviated by so associating the winding means with the resilient body that the winding mechanism, as well as other parts of the motive mechanism, is fully enclosed therein and sealed against air, water, dirt, etc.; the use of attachable and separate winding instrumentalities is no longer necessary; all parts of the motive mechanism are disposed within the resilient ball body and there is no projection of any part thereof beyond the ball body; and the winding operation is accomplished by mere distortion of the ball body by squeezing, pressing, or pushing, all of which operations are capable of performance, with ease, by all users, even infants of early age.

In its broadest aspect this invention consists in imparting to the ball body, in addition to its mechanism enclosing function, an additional function in cooperation with the power storage means, or as a means for applying force to energy storage means or mechanism enclosed therein.

In the drawing:
55 Figure 1 is a view, in perspective, of an em-

bodiment of the invention as applied to a flexible ball body, the ball body being indicated in dash lines, and a portion of the mechanism therein being broken away in the interest of clearness of disclosure;

Figure 2 is an enlarged sectional view taken on the line 2—2 of Figure 1, the supporting frame and ball body being omitted in the interest of clearness;

Figure 3 is a view of the structure, in elevation, as seen from the side substantially opposite that shown in Figure 1 as indicated by the line 3—3, Figure 2, with the winding rack omitted; and

Figure 4 is a fragmentary view, in elevation, of the mechanism showing the part of the ratchet mechanism indicated by the line 4—4, Figure 2.

Referring to the drawing in detail, and with reference particularly to Figure 1, it will be seen that the ball body 1, indicated in dash lines, encloses a flexible frame of skeleton type generally designated 2 which frame is hereinafter designated the supporting frame or mechanism supporting frame as distinguished from the herein-after described motor frame 20.

Supporting frame 2 is preferably formed of flexible and resilient metal members, such as wires or flat metal strips 3, which are rigidly secured together, as shown, to form a resiliently deformable, flexible, skeleton framework capable of close conformation with the interior surface of the ball body 1, to which it is secured in any suitable manner as by friction, adhesive, or mechanical fastening means such as bolts or rivets. If desired, this supporting frame may be omitted and the mechanism may be secured directly to the ball body. As shown in Figure 1 the frame consists of two circular members fixed at right angles to each other, and the lower half of the sphere has an additional semi-circular member secured thereto.

One of the members 3 is provided with a flattened portion 4 having therein a bearing bore or aperture 5. One end of the winding rack supporting shaft member 6, is supported for free rotation in the bore or aperture 5, and relative axial movement of the shaft member 6 with respect to the flattened portion 4 is prevented by means of thrust washer or collar members 7 disposed on opposite sides of the flattened portion 4, and pin members 8 secured to the shaft member 6 adjacent the washer members 7 as shown in Figure 3.

Rack stem member 9 is fixedly secured at the upper or outer end thereof to the shaft member 6, and has the main portion thereof, which is offset, spaced from, and in parallelism with shaft member 6 when said main portion will move outwardly under certain conditions with respect to shaft 6. Rigidly secured to and supported by this latter main portion of the member 9 is the rack member 10, provided with teeth 11 at one edge. As will be clearly understood, deformation of the supporting frame 2 by movement of the flattened portion 4 inwardly, by application of force substantially in the direction indicated by arrows A, A, will cause inward linear movement of the shaft member 6 and the winding rack or rack member 10, which rack member 10 is guided in a manner which will be hereinafter fully described. Due to the construction of the supporting frame 2, application of force substantially in the direction designated by arrows B, B, will cause similar compression of the frame 2 and

consequent inward linear movement of rack member 10.

The member 3 upon which is the flattened portion 4 and bore or aperture 5 is also provided, at 5 a point substantially opposite the bore or aperture 5, with a slot 12. This slot 12 receives the flattened portion 15 of the stationary shaft member 14. The stationary shaft member 14 is fixed to the frame 2, against rotation, by cooperation of the flattened portion 15 thereof with the slot 12, and axial movement of member 14 is prevented by pin members 16 secured to shaft member 14 at opposite sides of the connected members 3, as shown in Figure 3.

The stationary shaft 14 rotatably supports, with shaft 6, the motor frame 20, which carries the energy mechanism which, of course, includes power storage means responsive to reciprocation of rack member 11. Rigidly secured to the upper, or inner end of shaft 14 is a stationary gear member 17 with which a driven crown gear 44 cooperates, as hereinafter described, to cause rotary motion of the motor frame 20 substantially about the axis of the stationary shaft member 14.

25 Also rigidly secured to the stationary shaft 14 are a pair of spaced collar members 18 between which is disposed a supporting flange 22 depending from frame 20, which flange 22 is rotatable with respect to the stationary shaft 14, though 30 prevented from movement axially thereon by means of the collar members 18.

The motor frame, which is generally designated 20, is preferably stamped from a single metal sheet and is provided with a wall 21 in substantial 35 parallelism to a plane common to rotatable shaft member 6 and stationary shaft member 14.

Wall 21 terminates at its lower or outer end, in the before mentioned bent up supporting flange 22 which is provided with a bore or aperture through which the stationary shaft member 40 14 extends. Flange 22 is restrained against movement axially of the stationary shaft 14 by the collar members 18, as described above. Also struck out from wall 21 is flange 23 which is 45 provided with a bearing bore or aperture which supports the upper, or inner, end of the stationary shaft member 14 beyond, or inwardly of, the stationary gear 17.

Extending at substantially a right angle to the 50 wall 21 and between side wall 26 and wall 21, is a wall portion 24 with a slot 25 therein adjacent its junction with the wall 21, the side wall 26 being offset from the portion 24 as shown in Figure 2. Side wall 26 terminates in flange 27 55 extending therefrom at substantially a right angle and disposed substantially parallel to wall 21.

A bearing bore or aperture 28 is provided in flange 27 which is in registry with a similar bearing aperture 29 in wall 21 of frame 20, (Figure 2).

60 Rotatably supported in bearing apertures 28 and 29 is rotor shaft 30 which is surrounded by washer 31 adjacent the bearing aperture 28. A pin 32 cooperates with this washer and with a spring driven disk member 33 to prevent excessive axial movement of the rotor shaft 30 in the bearing bores or apertures 28 and 29, (Figure 2). As 65 will be understood, rotation of the spring driven disk member 33 will cause rotation of the rotor shaft 30, in the same direction.

Freely rotatable on the rotor shaft member 30 adjacent the wall 21 of the frame 20 is the winding gear member 34 which has the teeth thereof engaged, on the one side, by the teeth 11 of the rack member 10, and which has the teeth ex-

tending, at the opposite side, through the slot 25 in the wall portion 24 of the motor frame 20. Winding gear 34 has an integral offset disk member 35. An elongated spacer sleeve 36 is disposed between the spring driven disk member 33 and the disk member 35 and forms the supporting barrel for the spring 37 which has one end secured to the disk member 33 and the other end secured to the disk member 35 as shown in Figure 2.

An edge portion of the wall 21 is bent over at 38 to form a guide for the rotatable shaft member 6 in its reciprocation.

Secured at one end to the wall 21, as shown in Figure 2, is a flat retainer spring member 39 which retains the teeth 11 of the rack 10 in engagement with the teeth of winding gear 34 on the downward or inward (winding) stroke of the rack 11. The rack retainer member 39 yields, however, on the upward or outer (return) stroke of the rack 10 to permit the rack teeth 11 to pass the teeth of winding gear 34 which is then held stationary because its unidirectional rotation takes place in the opposite sense or direction.

The means for maintaining the rotation of the winding gear 34 unidirectional or clockwise only as seen in Figure 1, as indicated by the arrow thereon, is shown in detail in Figure 4 and comprises the rectangular loop member 40 having its upper end supported pivotally on the wall portion 24 adjacent an end of the slot 25 by the bracket member 41. The opposite end of the loop member 40 is constantly urged toward the wall portion 24, and the teeth of gear 34 which project through the slot 25 therein, by the biasing leaf spring member 42 which is fixedly secured at one end 43 to the wall portion (Figs. 2 and 4).

Outside the wall 21 the rotor shaft 30 has pinned thereto, the crown gear 44, the teeth of which mesh with the teeth of the stationary gear member 17, which is, as described above, rigid on the stationary shaft member 14. Rotation of the crown gear 44, therefore, because of its meshing engagement with the stationary gear 17, will cause rotation of frame 20, and supporting parts, about the axis of the stationary shaft 14 in the direction shown by the arrow in Figure 1.

Beyond crown gear 44, the outer, free, end of rotor shaft 30 is bent at an angle and the extremity thereof is provided with a weight member 45, preferably of spherical form, and which swings in an arc about the axis of the straight, supported, portion of the rotor shaft 30.

As pointed out above, however, this axis rotates about the axis of stationary shaft member 14, therefore, the weight member 45 has a compound motion imparted thereto. This compound motion of the weight member 45 will cause irregular rolling motion of the ball body 1 which, in seeking to maintain the weight member 45 always at the lowest point, (because of gravitational phenomena) will roll in an irregular and highly entertaining manner over any surface upon which it is supported. This motion will continue until the spring 37 becomes so far unwound as to be incapable of causing further motion of the weight member 45.

A notable feature of the above described mechanism is the fact that the spring member 37 may be partially wound by a single downward or inward (winding) stroke of the rack 11, or to any desired degree by continued intermittent reciprocation of the rack member 11 through intermittent distortion of the ball body 1.

Operation

The "at rest" position of the mechanism is illustrated in Figure 1.

To initiate operation of the ball pressure is applied to the body 1 substantially in either of the directions designated by arrows A, A, and B, B, as described above. This pressure deforms the body 1 and is translated into inward linear movement of the rotatable shaft member 6 and the fixedly attached rack member 10. The engagement of the rack teeth 11 with the teeth of winding gear 34 causes rotation of this winding gear member 34 in the direction shown by the arrow in Figure 1 throughout the downward or inward (winding) stroke of the rack 10. The winding of the spring 37 will occur during this rotation of the winding gear member 34 and will be accompanied by rotation of rotor shaft 30 about its axis and rotation of the frame 20 about the axis of stationary shaft member 14.

At the end of the inward (winding) stroke of rack 10, winding gear 34 will be restrained from reverse rotation by the means 40, 42 as described above, and the retainer member 39 will yield to permit the rack teeth 11 to pass the teeth of restrained winding gear member 34 as the rotatable shaft 6 and rack 10 are drawn upwardly or outwardly to starting position. The cycle may be repeated until spring 37 is fully wound but the single winding stroke will suffice to store, in spring 37, sufficient energy to cause substantial irregular motion to the body 1 as the weight member 45 describes its orbit about the axis of the supported portion of the rotor shaft 30 which axis is concurrently moving about the axis of stationary shaft 14, as described above.

The favorable ratio of winding permits of energy storage in spring 37 despite concurrent rotation of rotor shaft 30 so that it is unnecessary to prevent movement of rotor shaft 30 and frame 20 during winding.

It will thus be seen that I have provided motor means including energy storage means, and means for storing energy in the power storage means, which latter means cooperates with the deformable mechanism enclosing body and is operated by deformation thereof to accomplish the storage of energy in the motor means.

It is, of course, to be understood that the above described structure is merely illustrative of the application of the principles of my invention which is capable of various modifications and that I desire to comprehend such modifications as are embraced within the appended claims, and the invention.

Having disclosed and described a means by which I obtain the objects of my invention, I claim:

1. In combination, a fully closed deformable body, mechanism including an energy storage element supported in said body, and means associated with said deformable body and operable by deformation thereof for storing energy in said energy storage element.

2. In combination, a completely closed deformable body, spring motor means supported in said body and including a winding gear, and reciprocable rack means operatively engageable with said winding gear in at least one direction of movement for winding said spring motor means, said rack means being reciprocable through deformation of said body.

3. In combination, a completely closed deformable body, spring motor means supported within

said body and including a winding gear, and reciprocable rack means operatively engageable with said winding gear in at least one direction of movement for storing energy in said spring motor means, and means actuatable through deformation of said body for effecting reciprocation of said rack means.

4. In a toy, completely closed deformable body means, motor means in said body means, rack operable energy storage means associated with said motor means, and rack means associated with said deformable body means and having operative engagement with said energy storage means, said rack means being reciprocable through deformation of said body means for storing energy in said energy storage means.

5. In a toy, a resilient hollow body, a mechanism supporting frame in said body and deformable through application of pressure to said body, motion imparting means supported by said supporting frame, and means in said motion imparting means responsive to deformation of said supporting frame through application of pressure to said resilient hollow body for storing energy in said motion imparting means.

6. In a toy, a completely closed deformable body, frame means compressible through deformation of said body, motor means including energy storage means, weight means swingable by said motor means about an axis of said motor means, and means responsive to compression of said frame means for storing energy in said energy storage means for causing swinging motion of said weight means about said axis.

7. In structure according to claim 6, means providing operative connection between said motor means and said frame means for causing rotation of said motor means relative thereto during said motion of said weight means.

8. In a toy, motion imparting mechanism including energy storage means, a compressible body providing complete enclosure of said motion imparting mechanism, and means associated with said compressible body and responsive to compression thereof for storing energy in said energy storage means.

9. In a toy, a deformable closed body, motor means in said closed body and including energy storage means, gear means rotatable for storing energy in said energy storage means, and means operative upon distortion of said body for rotating said gear means and storing energy in said energy storage means.

10. In a toy, a completely closed deformable body, motor means including energy storage means within said body, means responsive to deformation of said body for storing energy in said energy storage means, rotatable shaft means driven by said motor means and having a straight portion and a bent end portion, and weight means on said bent end portion swingable in an arc about the axis of said straight portion during rotation of said shaft means.

11. In a toy, a completely closed deformable body, motor means including energy storage means within said body, means responsive to deformation of said body for storing energy in said energy storage means, rotatable shaft means driven by said motor means and having a straight portion and a bent end portion, and weight means on said bent end portion swingable in an arc about the axis of said straight portion during rotation of said shaft means, and an operative connection between said rotatable shaft and said body for translation of rotation of said shaft

means into swinging motion of said motor means and said shaft means about a fixed axis.

12. In a toy, a completely closed deformable body, motor means including energy storage means within said body, means responsive to deformation of said body for storing energy in said energy storage means, rotatable shaft means driven by said motor means and having a straight portion and a bent end portion, and weight means on said bent end portion swingable in an arc about the axis of said straight portion during rotation of said shaft means, and an operative connection between said rotatable shaft and said body for translation of rotation of said shaft means into swinging motion of said motor means and said shaft means about a fixed axis; said last named axis being substantially perpendicular to the axis of rotation of said shaft means.

20 13. In an automotive toy, a completely closed deformable body, motor means supported for driven swinging movement about an axis, therein, energy storage means in said motor means; and rotor shaft means driven by said motor means, said rotor shaft means including an end portion disposed at an angle to its axis of rotation, a weight member on said last named end portion, means responsive to deformation of said body for storing energy in said energy storage means, and means for translating stored energy into swinging motion of said motor means and rotation of said rotor shaft means for imparting compound motion to the weight on the angularly disposed end portion of said rotor shaft means, for effecting movement of said body.

25 14. In an automotive toy, a substantially spherical hollow deformable body, motor means supported for driven swinging movement about an axis, therein, energy storage means in said motor means; and rotor shaft means driven by said motor means about an axis substantially perpendicular to the axis of swing of said motor means, said rotor shaft means including an end portion disposed at an angle to its axis of rotation, a weight member on said last named end portion, means including a flexible skeleton frame responsive to deformation of said body for storing energy in said energy storage means, and means for translating stored energy into swinging motion of said motor means about its axis of swing and rotation of said rotor shaft means about its axis of rotation for imparting compound motion to the weight on the angularly disposed end portion of said rotor shaft means, for effecting rolling irregular movement of said body.

30 15. In a toy, a deformable skeleton frame structure, motor means supported within said frame structure and having energy storage means therein, and means providing operative connection between said frame structure and said energy storage means for translating deformation of said frame structure into storage of energy in said energy storage means.

35 16. In a device of the class described, a frame including a pair of flexible circular members secured together and disposed in planes substantially normal to one another, a pair of shaft members each having connection at one end with one of said circular members at substantially diametrically opposite points, one of said shaft members being fixed to said circular member and the other shaft being rotatable with respect to said circular member and secured against axial movement with respect thereto, operating

mechanism supported for driven rotation about said fixed shaft member, and for rotation with said rotatable shaft member, and rack means movable with respect to said rotatable shaft member by deformation of said frame for imparting motion to said mechanism.

17. In a toy, a flexible closed hollow body, and motion imparting means within said body and completely enclosed thereby whereby energy may be stored in said motion imparting means through deformation of said body and motion given said

body in response to release of energy from said motion imparting means.

18. In combination, a distortable completely sealed closed hollow body, and motion imparting means completely enclosed in said body, said motion imparting means including a weight member, means for imparting compound motion to said weight member, and means responsive to distortion of said closed hollow body for storing energy in said last named means.

JAMES SMITHWICK.
